US00D970487S

(12) **United States Design Patent** (10) Patent No.: **US D970,487 S**
(45) Date of Patent: ** Nov. 22, 2022

(54) **RANGE EXTENDER DEVICE**

(71) Applicant: **Amazon Technologies, Inc.**, Seattle, WA (US)

(72) Inventors: **James Siminoff**, Pacific Palisades, CA (US); **Mark Siminoff**, Mountain View, CA (US); **Wen-Yo Lu**, Pasadena, CA (US); **Christopher Loew**, Palo Alto, CA (US); **Jia Li**, Nutley, NJ (US); **Wei-Chung Wang**, New Taipei (TW); **Gregory Berlin**, Spring City, PA (US); **Andrew Louis Russell**, Havertown, PA (US)

(73) Assignee: **Amazon Technologies, Inc.**, Seattle, WA (US)

(**) Term: **15 Years**

(21) Appl. No.: **29/803,942**

(22) Filed: **Aug. 17, 2021**

CLAIM

The ornamental design for a range extender device, as shown and described.

DESCRIPTION

FIG. 1 is a front, top, right-side perspective view of a range extender device;

FIG. 2 is a back, bottom, left-side perspective view thereof;

FIG. 3 is a front elevation view thereof;

FIG. 4 is a back elevation view thereof;

FIG. 5 is a left-side elevation view thereof;

FIG. 6 is a right-side elevation view thereof;

FIG. 7 is a top plan view thereof; and,

FIG. 8 is a bottom plan view thereof.

(Continued)

The broken lines depict portions of the range extender device that form no part of the claimed design.

1 Claim, 8 Drawing Sheets
